DESIGN FOR A COMBINED HAIR CURLER
AND COMB

Mario Petitta, New York, N. Y.

Application May 29, 1947, Serial No. 139,351

Term of patent 3½ years

(Cl. D86—8)

To all whom it may concern:

Be it known that I, Mario Petitta, a citizen of the United States of America, residing in New York city, county of New York, and State of New York, have invented a new, original, and ornamental Design for a Combined Hair Curler and Comb, of which the following is a specification, reference being had to the accompanying drawing, forming part thereof, wherein

Figure 1 is a perspective view of a combined hair curler and comb, showing my new design.

Figure 2 is a similar view thereof, showing the hair curler and comb in separated position.

Figure 3 is an elevational view of the hair curler member, looking from the left of Figure 2.

The opposite sides of the hair curler and comb are identical in appearance to the sides shown.

I claim:

The ornamental design for a combined hair curler and comb, substantially as shown and described.

MARIO PETITTA.
